UNITED STATES PATENT OFFICE.

WILBER THOMAS, OF QUINCY, ILLINOIS.

DESIGN FOR A FENCE-PICKET.

SPECIFICATION forming part of Design No. 12,973, dated June 13, 1882.

Application filed April 21, 1882. Term of patent 14 years.

To all whom it may concern:

Be it known that I, WILBER THOMAS, of Quincy, in the county of Adams and State of Illinois, have invented and produced a new and original design for Fence Pickets, Palings, and the like; and I do hereby declare that the following is a full, clear, and exact description of the invention, which will enable others skilled in the art to which it appertains to make and use the same, reference being had to the accompanying drawings, which form a part of this specification.

This invention relates to designs for fence pickets, palings, and the like, and has for its object to secure simplicity, novelty, and attractiveness.

To this end it consists in certain improvements in the contour of the same, substantially as will be hereinafter more fully specified.

In the drawings, Figure 1 is a perspective view of a picket embodying my improved design. Fig. 2 is a cross-section of the same, and Fig. 3 is a view of a fence formed of my ornamental pickets.

Corresponding parts in the figures are denoted by the same letters of reference.

Referring by letter to the drawings, A designates an upright picket, of diamond shape in cross-section, and having its edges B flattened, so as to be smooth and square. The top C of the picket is beveled- Δ shaped, as shown, the vertex of this Δ -angle being at the points D D of the diamond.

The above-described ornamental picket is designed to be secured between the posts of the fence by longitudinal wires, as in Fig. 3, or any other suitable means, and when in position form a neat and very attractive fence at but little cost.

I claim and desire to secure by Letters Patent—

The improved design for ornamental fence pickets, palings, and the like, herein shown and specified.

In testimony that I claim the foregoing as my own I have hereunto affixed my signature in presence of two witnesses.

WILBER THOMAS.
